Primary Examiner—James R. Largen*Attorney, Agent, or Firm*—Hugh E. Smith[57] **CLAIM**

The ornamental design for a combined heated and illuminated toilet seat, as shown and described.

DESCRIPTION

FIG. 1 is a front elevational view of a combined heated and illuminated toilet seat showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof.

The broken line representation of a toilet in FIG. 7 is for purposes of illustration only and forms no part of the claimed design.

FIG. 1

FIG. 2

FIG. 3

FIG. 4

FIG. 5

FIG. 6

FIG. 7
